UNITED STATES PATENT OFFICE.

PIERRE P. GILLES, OF SPRINGFIELD, MASSACHUSETTS.

VACUUM-FEED CARBURETER.

1,350,151.

Specification of Letters Patent. Patented Aug. 17, 1920.

Application filed October 14, 1918. Serial No. 258,091.

To all whom it may concern:

Be it known that I, PIERRE P. GILLES, born in Switzerland of German parentage, now believing myself to be a citizen of the 5 Swiss Confederation, and having formally declared my intention of becoming a citizen of the United States of America in conformance with the United States immigration laws, and now residing at Springfield, 10 in the county of Hampden and State of Massachusetts, United States of America, have invented certain new and useful Improvements in Vacuum-Feed Carbureters, of which the following is a specification.

15 This invention relates generally to that class of devices, by means of which fuel may be drawn by suction from a low level supply tank into a carbureter. More particularly, the invention is concerned with 20 the provision of improvements, which are especially applicable to a vacuum feed carbureter, although the improvements are capable of general application, if desired. By a vacuum feed carbureter is meant a 25 unitary structure resulting from a consolidation of a carbureter with the vacuum feed fuel supply device. One type of vacuum feed carbureter is disclosed in my prior U. S. Letters Patent No. 1,240,842 granted September 25, 1917.

In the usual vacuum feed system, the outlet of the fuel supply or suction chamber is provided with an outwardly opening check valve and is then connected to a carbureter 35 of any standard type. All standard carbureters are provided with a float in the carbureter fuel chamber and the inflow of fuel to the latter is controlled by a needle valve, which is operated by rise and fall of the 40 float. The needle valve is, thus, the means ordinarily employed to regulate the fuel level in the carbureter and the check valve is provided, by necessity, to prevent inflow into the fuel supply chamber when suction 45 is applied thereto. The usual needle valve is a source of much trouble in that it sometimes does not seat accurately, and therefore leaks, and at other times sticks, and therefore fails to open at the proper time. 50 The regulation of fuel level by the usual float controlled needle valve is thus not as positive and accurate as could be desired. Moreover, two valves,—the needle and the check valve,—are employed, both separately 55 performing individual functions.

This invention has for its object to pro-

vide, in combination with a fuel feeding device and a carbureter, a single valve to control the communication between said device and carbureter and means operable from a 60 float in the carbureter to control the operation of the valve, characterized in that the one valve acts as a check valve for the fuel feeding device and controls the fuel level in the carbureter, as well. 65

Another object of the invention is to provide a combined fuel feeding device and carbureter; in which these two elements, generally used separately, are consolidated into a unitary structure, with the elimination of the usual needle valve control of the carbureter and the substitution of improved means, which are operable from the carbureter float and arranged to combine with the check valve of the fuel feeding device, 75 to the end that such check valve is made to perform its usual function and, in addition, the function of controlling the fuel level in the carbureter.

Other objects and advantages will appear 80 from the following description and from the illustrative embodiment of the invention in the accompanying drawings, in which:

The figure is a sectional elevational view 85 of a vacuum feed carbureter embodying the invention.

Referring to this drawing in detail; a fuel feeding device and a carbureter, (both of any suitable type and herein shown merely in a conventional and convenient illustrative form) are combined into a one piece, unitary structure. Such consolidation of the two known elements involves a casing A having two separate chambers B 90 and C, preferably arranged at different levels, as shown. Chambers B and C will be later referred to as the fuel supply and the carbureter fuel chambers, respectively. Chamber B is provided with a suitable 100 cover b which is so applied as to render the chamber substantially air-tight, except for certain passages to be later described. Chamber C preferably also has a cover, as c, although this is not absolutely essential, 105 and if provided means, as an opening d in the wall of chamber C, should be provided to insure that the latter will be subjected to atmospheric pressure.

The fuel supply chamber B is provided 110 with a fuel inlet f adapted for connection to a low level supply tank; an air inlet g; and

a passage *h* which is adapted for connection to suction means. These three passages may conveniently be provided in the cover *b*. Means are provided so that the chamber *B* is alternately subjected to suction and atmospheric pressure and such means are controlled by the level of fuel in the chamber. Any suitable means may be provided for this purpose and that chosen is merely by way of illustrative example of one suitable means. As illustrated, a valve *i*, supported by the free end of a pivoted arm *j*, is arranged to open or close the suction connection *h*, and a valve *k*, operable from an extension *l* of valve *i*, is arranged to open or close the air inlet *g*. The arrangement is such that valve *i* will open when valve *k* closes and vice versa. In order to operate these valves, a float *m* is provided in chamber *B* and such float is pivotally connected to the free end of an arm *n* which in turn is pivoted co-axially with arm *j*. A spring *o* connects the free ends of arms *j* and *n*. Thus, as float *m* falls, arm *n* will be gradually swung downwardly, but arm *j* will not be moved until the spring *o* is brought below the pivotal axis of the arms. At such time, arm *j* will be rapidly moved downwardly to open valve *i* and allow valve *k* to move to closed position. Upon a rising movement of float *m*, arm *n* will be gradually moved, but arm *j* will not be actuated until spring *o* has been brought above the pivotal axis of the arms, at which time the arm *j* will be suddenly moved to open valve *k* and close valve *i*. Thus, chamber *B* is alternately subjected to suction and atmospheric pressure for the purpose of drawing fuel therein from the low level tank and permitting such fuel to pass therefrom by gravity flow, all in a manner well understood by those skilled in the art.

The chamber *C* is the carbureter fuel chamber,—the equivalent of the usual float chamber. Any suitable or desirable carbureter structure may be provided and the present illustration is merely conventional. As illustrated, *p* represents (in cross section) the usual air intake pipe and *q* is a suitable nozzle or atomizing device, which is fed with fuel from chamber *C* by way of a short lateral passage *r*.

In order that fuel in the supply chamber *B* may pass by gravity flow into chamber *C*, a passage *s* is provided in casing *A*, which passage affords communication between the lower portion of chamber *B* and the chamber *C*, preferably above the level of fuel in the latter. In order that there shall be no return flow from chamber *C* to chamber *B*, a check valve *6* is provided for the passage *s* and such valve opens outwardly (in the direction of fuel flow) and into the chamber *C*. The valve *6* performs the usual function with relation to the fuel feeding de-

vice and is made to perform an additional function,—namely, the regulation of the fuel level in chamber *C*,—by the following means. A float *7* is provided in chamber *C* and the upper portion of such float is pivotally connected to the outer end of an arm *8* which is suitably pivoted at *9* to casing *A* and within chamber *C*. Arm *8* has an upwardly directed extension *10*, which, when the fuel in chamber *C* is at the desired predetermined level, engages valve *6* and holds it in closed position to prevent further flow to chamber *C*. As soon as the fuel in chamber *C* falls below the desired level, float *7* falls also and thereby arm *10* is moved toward the right, allowing valve *6* to open and the chamber *C* to be replenished with fuel.

Thus, I have provided in associated relation, a fuel feeding device and carbureter,—preferably consolidated into a unitary structure which I term a vacuum feed carbureter,—in which the fuel level in the carbureter is controlled in an improved manner by the check valve of the fuel feeding device.

The invention has been disclosed herein in one embodiment for the purposes of illustration, but the scope of the invention is defined by the appended claims rather than by the foregoing description.

What I claim is,—

1. A vacuum feed carbureter, comprising, a casing provided with chambers at different levels and a passage affording communication between the lower portion of the upper and the upper portion of the lower chamber, a float in the upper chamber, means controlled by said float to draw fuel into the upper chamber, an atomizing device in the lower chamber, a float in the latter, a single check valve controlling said passage and opening into the lower chamber, and means operable from the second float to close said valve when the fuel in the lower chamber reaches a predetermined level and to release said valve when the fuel in the lower chamber falls below such level.

2. A vacuum feed carbureter, comprising a fuel supply chamber, a float therein, a valve controlled by the float operable to draw fuel into said chamber, a second valve operable by said first-named valve to alternately subject said chamber to suction and atmospheric pressure, a carbureter fuel chamber, an atomizing device connected therewith, a passage connecting the chambers, a clack-valve normally closing said passage but adapted to be opened by the weight in the fuel supply chamber, a float in the carbureter fuel chamber, and means operable by said last-named float to positively close said last-named valve.

3. A vacuum carbureter, comprising a fuel supply chamber, a float therein, means controlled by the float operable to draw fuel into said chamber, a carbureter chamber, an

atomizing device connected therewith, a passage connecting the chambers, a clack valve normally closing the passage but adapted to be opened by the weight of the fuel in the 5 fuel supply chamber, a float in the carbureter fuel chamber, and a float operated bell-crank having a short arm bearing on said clack-valve and adapted to hold the same in closed position when the fuel in said 10 carbureter fuel chamber is at the desired predetermined level.

4. A vacuum carbureter, comprising a fuel supply chamber, a float therein, means controlled by the float operable to draw fuel

into said chamber, a carbureter chamber, an 15 atomizing device connected therewith, a passage connecting the chambers, a valve normally closing said passage but adapted to be opened by the weight of the fuel in the fuel supply chamber, a float in the carbureter 20 fuel chamber, and a float operated bell-crank having a short arm bearing on said valve and adapted to hold the same in closed position when the fuel in said carbureter fuel chamber is at the desired pre- 25 determined level.

PIERRE P. GILLES.
